CLAIM

The ornamental design for a combination face mask and beard net, as shown and described.

DESCRIPTION

FIG. 1 is a perspective view of a combination face mask and beard net showing my new design;
FIG. 2 is a front elevation view thereof;
FIG. 3 is a rear elevation view thereof;
FIG. 4 is a top plan view thereof;
FIG. 5 is a bottom plan view thereof;
FIG. 6 is a left side elevation view thereof;
FIG. 7 is a right side elevation view thereof; and,
FIG. 8 is a perspective view thereof, shown in a used condition on a human figure shown in broken lines.
The broken lines in the drawings depict portions of the combination face mask and beard net that form no part of the claimed design.
